BEET HARVESTER OR SIMILAR ARTICLE

Harold E. Erdman, Rte. 1, Crookston, Minn.

Filed Feb. 6, 1962, Ser. No. 68,687

Term of patent 14 years

(Cl. D40—1)

FIG. 1

FIG. 2

FIG. 3

FIG. 4

FIG. 5

FIG. 1 is a perspective view taken from the right side of a beet harvester or similar article embodying my new design;

FIG. 2 is a perspective view taken from the left side thereof;

FIG. 3 is a top view thereof taken in perspective from the left side;

FIG. 4 is a front perspective view thereof; and

FIG. 5 is a rear perspective view thereof.

The dominant features of my design reside in the portions shown in full lines.

I claim:
The ornamental design for a beet harvester or similar article, as shown and described.
